Primary Examiner — Richard E Chilcot*(74) Attorney, Agent, or Firm* — Andrew Wilford(57) **CLAIM**

The ornamental design for a medical apparatus and equipment, as shown and described.

DESCRIPTION

FIG. 1 is a perspective view of the invention;

FIG. 2 is a left-side elevational view of the invention, the

right-side elevational view being a mirror image thereof;

FIG. 3 is a front elevational view of the invention;

FIG. 4 is a back elevational view of the invention; and

FIG. 5 is a top view of the invention, details that would be visible in a bottom view being disclaimed.

1 Claim, 5 Drawing Sheets(56)
